UNITED STATES PATENT OFFICE.

FREDRICK HEIN, OF OLEAN, NEW YORK.

ALARM-BELL.

SPECIFICATION forming part of Letters Patent No. 634,727, dated October 10, 1899.

Application filed February 1, 1899. Serial No. 704,163. (No model.)

To all whom it may concern:

Be it known that I, FREDRICK HEIN, of Olean, county of Cattaraugus, and State of New York, have invented certain new and useful Improvements in Alarm-Bells, of which the following is a full, clear, and exact specification, reference being had to the accompanying drawings, wherein—

Figure 1 is an elevation, Fig. 2 a side view, and Fig. 3 a detail view, of the alarm-operating mechanism.

My invention relates to signaling devices; and it consists of the hereinafter-described apparatus for audibly signaling when water in a tank or receptacle reaches a certain predetermined level.

The apparatus consists of a bell, an automatic spring-movement for ringing the bell, and of mechanism for arresting and releasing the movement of the bell by a floating weight suspended in the tank and acting upon a crank-lever secured to the arbor of the bell-movement.

The bell-movement is mounted between plates 1 and 2, which are combined by studs 3 into a frame that may be secured in place by screws 4 passing through lugs 5, which are integral with the back plate 2. The bell-movement is actuated by spring 6, wound around shaft 26 and having one end secured to this shaft and the other to one of the studs 3. The end of shaft 26 projecting from the plate 1 is square or otherwise adapted to receive a key 27, by means of which the spring 35 is wound up by turning the shaft from right to left. When released, the spring strives to unwind, and thereby imparts to the shaft a rotary motion in opposite direction. On the same shaft 26 is set a cog-wheel 7 and is 40 coupled thereto by ratchet-wheel 8, which is rigidly secured to the shaft, and pawl 9, pivotally secured to wheel 7 and pressed against the ratchet-wheel 8 by spring 10. Shaft 13 is mounted above the shaft 26, and on this 45 shaft rotate the escapement-wheel 12 and pinion 11, which is integral therewith. The teeth of wheel 7 mesh with the teeth of the pinion 11, and thus wheel 7 drives the escapement-wheel 12. Escapement 15 is secured to oscillating arbor 14, which is mounted to one side of and above shaft 13. Pallets 16 and 17 of the escapement 15 engage

alternately with the teeth of the escapement-wheel 12 and receive thereby a reciprocating motion, which is imparted to the arbor 14 when the escapement-wheel 12 is rotated. Stem 23 of the striker 24 is rigidly secured to the same arbor 14, and when this arbor 14 is oscillated by the reciprocating motion of the escapement 15 striker 24 is moved to and from the bell 25 and rings it. The action of the movement is arrested by turning arbor 14 downwardly, so that pallet 17 of the escapement 15 rests against the face of the corresponding tooth of the escapement-wheel 12 and is pressed upon it with sufficient force to prevent its motion. This is done by crank-lever 18, whose one end is secured (riveted) in the arbor 14 and whose other end is weighted by suspending floater 19 from it. This floater is of such weight as to produce sufficient pressure upon the pallet 17 to overcome the driving force of the escapement-wheel 12, while its full weight acts on the end of the lever 18. Crank-lever 18 is suitably bent, so that when the alarm apparatus is affixed on the outside of the tank the floater 19 swings in the tank. Floater 19 is provided with a stem 20, which is passed through eye 21, provided on the end of the crank-lever 18, and is held in engagement with the lever by knob 22, secured to the stem. When the water rises in the tank to a predetermined level, it reaches the floater 19, it relieves lever 18 from its weight, and as thereby the pressure exerted by pallet 17 upon the escapement-wheel 12 ceases the bell-movement is set free and rings the bell, thus announcing that the water in the tank has reached the predetermined level.

To insure raising the floater in a vertical motion, I provide the sleeve 26 in connection with the eye 21, whereby any twisting tendency and friction in the operation of the apparatus are avoided.

The alarm acts when the level of the water reaches the predetermined level, which is indicated by the position of the floater in the tank, and continues to act as long as the level of the water remains above its desired height.

The construction of the apparatus is very simple and very effective and reliable for the purpose designated.

I claim as my invention and desire to secure by Letters Patent—

1. An apparatus, for audibly signaling when the water in a tank or receptacle reaches a certain predetermined level, the apparatus consisting of a bell, an automatic movement for ringing the bell, comprising an escapement-wheel, an arbor and an escapement secured thereto and engaging with the escapement-wheel, and means for driving the escapement-wheel, a crank-lever secured to the arbor, and a floating weight constantly engaging the end of the crank-lever and pressing the pallet of the escapement against the teeth of the escapement-wheel.
2. The combination with an automatic movement for ringing an alarm-bell, comprising an escapement-wheel, an arbor and an

escapement secured thereto and engaging with the escapement-wheel, and means for driving the escapement-wheel, of a crank-lever secured to the arbor, an eye on the free end of the lever, a floating weight having a stem engaging with the eye of the crank-lever, a removable head secured to the stem above the eye of the crank-lever and holding the floating weight constantly engaged with the lever whereby the pallet of the escapement is held against the teeth of the escapement-wheel.

FREDRICK HEIN.
